UNITED STATES PATENT OFFICE.

THOMAS ROGERS, OF PHILADELPHIA, PENNSYLVANIA.

MAIL-BAG CATCHER.

Application filed March 12, 1924. Serial No. 698,621.

To all whom it may concern:

Be it known that I, THOMAS ROGERS, a citizen of the United States, residing at Philadelphia, in the county of Philadelphia 5 and State of Pennsylvania, have invented certain new and useful Improvements in Mail-Bag Catchers, of which the following is a specification.

My invention relates to mail bag catchers, 10 and its objects are to provide means whereby mail bags may be delivered from the mail car to the station and taken from the station aboard the car without stopping it, and to provide means which will hold the bag, after 15 being delivered to or taken from the station, on the catching means.

These objects, and other advantageous ends which will be described hereinafter, I attain in the following manner, reference 20 being had to the accompanying drawings in which—

Figure 1 is a side elevation of a mail bag catcher constructed in accordance with my invention illustrating it about to deliver 25 and catch a mail bag,

Figure 2 a left hand edge view of Figure 1 showing the mail car partly in section,

Figure 3 a side elevation showing the 30 mail bag delivered to and taken from the station by the mail car,

Figure 4 a plan view of Figure 1 showing the mail car in section, and

Figure 5 a section on line 5—5 of Figure 35 1.

Referring to the drawings, 1 indicates a mail car having an arm 2 pivoted thereto at 3 and locked in operative position by a pivoted bolt 4. A handle 5 is preferably 40 secured to the arm to facilitate swinging the arm into and out of the mail car. A standard 6 embedded in a foundation 7 has a baffle plate 8 pivoted thereto at 9. This plate, when in the position shown in Figures 1 and 2, is adapted to prevent the mail bag from swinging after being caught as shown in Figure 3 and may be swung out of the way when not in use, as shown in dot-and-dash lines in Figure 5.

50 The means for catching the bag and for holding it in position to be caught are mounted on arm 2 and standard 6, their construction being similar, but one will be described. The means for holding the bag in 55 position to be caught includes a support 10 having a notch 11; a ring 12 bent inward

to form a loop 13 which rests in notch 11, and a mail bag hook 14 suspended from the ring at opposite sides of the loop. A mail bag 15 is placed on the hook. Having loop 60 13 bent inwardly from the ring and suspending the mail bag hook 14 from the ring at opposite sides of the loop, ring 12 will always be held upright and in position to be caught. The means for catching the ring 65 includes a yoke 16 having a latch 17 pivoted on its upper arm and normally engaging a stop 18 on its lower arm. This latch 17 allows ring 12 to pass between the arms of the yoke into the space 19 but will not allow 70 the ring to be accidentally moved out of space 19. The holding and catching means are fixed to arm 2 and pivotally connected on standard 6 so that they may be swung into the mail car and out of the way on the 75 standard when not in use.

The holding means and the catching means are pivoted on the standard in a similar manner and only one pivot will be described. Arms 20, pivoted to standard 6 at 21, carry 80 the holding means and the catching means. A pivoted locking finger 22 passes through a hole 23 in one of a pair of bracket flanges 24 which pivotally support arms 20. A similar locking finger is used for holding plate 85 8 in position.

To deliver a mail bag from the car to a station, a mail bag is placed on hook 14, and loop 13 placed in notch 11. The mail bag is then swung on arm 2 into position to be 90 caught. Latch 4 locks arm 2 in position. As the car travels past the station, ring 12 will engage latch 17 and pass into space 19 where it will engage the yoke and thereby be dragged off support 10. The mail bag 95 will engage baffle plate 8 and be prevented from swinging on yoke 16. To take a mail bag from a station aboard the car, a mail bag is placed on hook 14, and loop 13 placed in notch 11 in support 10 which is pivoted on standard 6. The mail bag is then swung on arm 20 into position to be caught. Locking bolt 22 holds arm 20 in position against 100 swinging. As the car travels past the station ring 12 will engage latch 17 and pass into space 19 where it will engage the yoke and thereby be dragged off support 10. The mail bag is then swung on arm 20 into position to be caught. Locking bolt 22 holds arm 20 in position against 105 swinging. As the car travels past the station ring 12 will engage latch 17 and pass into space 19 where it will engage the yoke and thereby be dragged off support 10. The mail bag is then swung on arm 20 into position to be caught. Locking bolt 22 holds arm 20 in position against 110 swinging. As the car travels past the station ring 12 will engage latch 17 and pass into space 19 where it will engage the yoke and thereby be dragged off support 10. The mail bag is then swung on arm 20 into position to be caught. Locking bolt 22 holds arm 20 in position against 115 swinging.

With a mail bag catcher as above set forth the mail bag may be delivered to or taken from the station without danger of it being thrown under the wheels of the train 5 or otherwise injured, and the mail bags may be easily placed on and taken off the catcher.

While I have described my invention as taking a particular form, it will be understood that the various parts may be changed 10 without departing from the spirit thereof, and hence I do not limit myself to the precise construction set forth, but consider that I am at liberty to make such changes and alterations as fairly come within the scope 15 of the appended claims.

Having thus described my invention, what I claim as new and desire to secure by Letters Patent is:—

1. A mail bag catcher including a support 20 having a delivery head formed with a transversely notched top portion and with an inclined bottom portion below said notched top portion; a ring member bowed inwardly upon itself to form a loop adapted to rest in 25 the transverse notch; a yoked mail bag hook suspended from said ring member at opposite sides of the loop thereof, the bight portion of said yoked hook coming under the inclined bottom portion of said head; and

means adapted to seize said ring member 30 and drag it from said head in a direction away from said inclined bottom portion, substantially as described.

2. A mail bag catcher including a support 35 having a delivery head formed with a transversely notched top portion and with an inclined bottom portion below said notched top portion; a ring member bowed upon itself to form a loop adapted to rest in the transverse notch; a yoked mail bag hook suspended from said ring member at opposite sides of the loop thereof, the bight portion in said yoked hook coming under the inclined bottom portion of said head; a yoke 40 member adapted to seize the ring and drag 45 it from said head and comprising arms having inwardly converging portions providing a passage into an expanded ring member carrying chamber, and a stop shoulder guarding the exit from said chamber, substantially as described.

In testimony whereof I have signed my name to this specification in the presence of two subscribing witnesses.

THOMAS ROGERS.
